UNITED STATES PATENT OFFICE.

EDWARD R. HALLAM, OF NEW HAVEN, CONNECTICUT, AND THOMAS B. BARNARD, OF BROOKLYN, NEW YORK, ASSIGNORS TO E. R. HALLAM.

IMPROVEMENT IN GAS-METERS.

Specification forming part of Letters Patent No. 9,586, dated February 8, 1853.

To all whom it may concern:

Be it known that we, EDWARD R. HALLAM, of New Haven, in the county of New Haven and State of Connecticut, and THOMAS B. BARNARD, of Brooklyn, Kings county, and State of New York, have invented a new and useful Machine for Measuring Gas by Volume; and we do hereby declare that the following is a full, clear, and exact description of the construction and operation of the same, reference being had to the annexed drawings, making a part of this specification, in which—

Figure 1 is a perspective view, Fig. 2 a side elevation, Fig. 3 a ground plan, Fig. 4 a horizontal section, and Fig. 5 a vertical section, of the machine. Fig. 6 is a side elevation, Fig. 7 a ground plan, and Fig. 8 an end view, of the apparatus for working the valves.

The same letters of reference denote the same parts in each of the figures.

A is the external cylinder, to the bottom of which is fastened an inner cylinder, t, thereby forming an annular space, u.

B is a cylinder with a hollow ring, w, at the bottom, which serves as a float to counterbalance the weight of the cylinder B, the annular space u being filled with water or other liquid up to the line x z.

l is the receiving-pipe, through which the gas passes into the valve-box and thence into the cylinder B through the pipe g, or into the space above the cylinder B through the pipe n.

h is the delivering-pipe, through which the gas passes from the space within the cylinder B through the pipe f, or from the space above the cylinder B through the pipe m, to the valve-box y, and thence to the burners.

h and i are the valves by which the gas is directed in its course through the pipes g n f m.

c is the beam that works the valves h and i by means of the rods a and b.

e is a hollow tube attached to the beam c by a center, o, on which it can vibrate.

l' is a bent wire (see Figs. 6, 7, and 8) for the tube e to strike against when it is raised

or lowered by the cylinder B by means of the button w' and cord v'.

c' is a stationary bearer fixed to the cylinder A, and carries the beam c, &c.

B' is the center or pivot of the beam c.

E is a bracket carrying the end of the pivot B'.

Operation: The gas, being received through the pipe l into the valve-box v, flows through the pipe g into the space within the cylinder B, but is prevented from passing into the pipe n by the valve i and prevented from flowing out of the cylinder B by the valve h until the cylinder B is full, when it raises the hollow tube e, and then the mercury or other fluid that is in the tube runs down to the other end, causes the tube to turn on its center o and to strike the bent wire l' and turn the beam c, forcing down the valve i and raising the valve h. Then the gas within the cylinder B is allowed to flow out through the pipe f, and thence through the pipe k to the burners, and the gas flowing through the receiving-pipe l is allowed to pass up the pipe n into the space above the cylinder B, but is prevented from passing out of this space by the valve h till the cylinder B has descended to its required distance, when the cord v' pulls down the tube e and allows the fluid within it to run back to its former position, when it turns upon the center o, and, striking the lower part of the bent wire l', turns the beam c back to its first or former position and changes the valves, so as to allow the gas to flow into the cylinder B and out of the space above it, and so on.

The quantity of gas passed through this machine is measured by the cylinder B, which may be made to work an index on the top of the machine by means of a wire or rod working through a stuffing-box on the top of the cylinder A, one end of which wire is attached to the index. The other end projects below the stuffing-box and into the cylinder A sufficiently for the cylinder B to strike it and raise it when the said cylinder B gets to its full height, and thereby moving the index. The index is not shown on the drawings, pre-

suming it unnecessary, as any ordinary index can be attached.

What we claim as our invention, and desire to secure by Letters Patent, is—

The within-described method of constructing meters with one cylinder working within another, so that the gas passes alternately into the inner cylinder and out of the space above it and then out of the inner cylinder,

while the supply enters the space above it, the gas being changed in its course or direction by valves, as herein described.

E. R. HALLAM.
THOS. B. BARNARD.

In presence of—

ALFRED H. TERRY,
E. STOCKWELL.
